UNITED STATES PATENT OFFICE.

WALTER BALLARD, OF OAKLAND, CALIFORNIA, ASSIGNOR OF ONE-HALF TO GEORGE BALLARD, OF OAKLAND, CALIFORNIA.

VALVE.

1,140,017.

Specification of Letters Patent. Patented May 18, 1915.

Application filed September 10, 1913. Serial No. 789,112.

To all whom it may concern:

Be it known that I, WALTER BALLARD, a citizen of the United States of America, residing at Oakland, in the county of Alameda and State of California, have invented 5 new and useful Improvements in Valves, of which the following is a specification.

This invention relates to improvements in fluid controlling valves and has particular 10 application to a valve of the class described for controlling fluid operated motors.

In carrying out the present invention, it is 15 my purpose to improve and simplify the general construction of fluid controlling valves and to provide a valve which will operate efficiently and effectively for its intended purpose and which will embody few parts and these so correlated and arranged as to reduce the possibility of derangement 20 to a minimum.

With the above and other objects in view, the invention consists in the construction, combination and arrangement of parts hereinafter set forth in and falling within the 25 scope of the claim.

In the accompanying drawings; Figure 1 is a vertical sectional view through a controlling valve constructed in accordance with the present invention. Fig. 2 is a horizontal 30 sectional view therethrough taken on a line approximately centrally of Fig. 3.

Referring now to the drawings in detail, 15 designates a casing provided between its ends with inlet and discharge ports 17 and 18 respectively disposed at diametrically opposite points upon the casing and adapted to form connections between the casing and the inlet pipe to the motor (not shown) controlled by the valve. Also formed in the 20 casing 15 between the inlet and discharge ports therein is a port 19 opening into the atmosphere. Mounted for sliding movement within the casing is a plug 20 formed with a transverse bore 21 adapted to establish 25 communication between the ports 17 and 18 so that the fluid may flow through the intake pipe to the motor. Interposed between one end of the casing and the front end of the plug 20 is a coiled expansion spring 22 acting 30 upon the plug 20 to hold the bore 21 normally out of communication with the ports

17 and 18. Also formed in the plug 20 is an angle passage 23 which, when the plug is in normal position and the bore 20 out of communication with the ports 17 and 18, 55 establishes communication between the discharge port 18 and the port 19 opening into the atmosphere so that the motor will be in open communication with the atmosphere. The free end of the plug 20 is provided with 60 a stem 24 disposed in the path of movement of an operating lever, (not shown) adapted to impact against the lower end of the stem and force the plug upwardly against the action of the spring 22. Thus, when the 65 plug 20 within the casing 15 is moved upwardly against the action of the spring 22 communication between the motor and the atmosphere is cut off and communication between the motor and the source of supply 70 established.

I claim:

A valve for the purpose described comprising a cylindrical casing having axially alining inlet and discharge ports formed 75 therein and a port opening into the atmosphere and disposed between the first-mentioned ports and in the same plane with such ports, a plug within said casing and adapted to slide therein and formed with a bore 80 adapted to register with said inlet and discharge ports, and with an angle passage disposed above the bore therein, a spring interposed between one end of said casing and the adjacent end of the plug and acting upon 85 the plug to hold the bore therein normally out of engagement with the inlet and discharge ports and the angle passage in communication with the discharge port and the atmospheric port whereby the discharge port 90 will be opened to the atmosphere and the stem connected to the remaining end of said plug and projecting outwardly of the adjacent end wall of said casing whereby the plug may be actuated against the action of 95 the spring.

In testimony whereof I affix my signature in presence of two witnesses.

WALTER BALLARD.
